PREVENTION OF FOAMING IN STEAM
GENERATION

Paul G. Bird and Arthur L. Jacoby, Western
Springs, and Robert W. Kell, Oak Park, Ill., as-
signors to National Aluminate Corporation,
Chicago, Ill., a corporation of Delaware

No Drawing. Application March 27, 1942,
Serial No. 436,495

12 Claims. (Cl. 252—321)

1

The present invention relates to antifoaming compositions which are used in steam boilers and similar steam generators, evaporators, etc., to overcome the tendency of the water therein to foam and hence to bring about the priming of the steam generator or the like.

One of the objects of the present invention relates to a liquid for the generation of steam in steam generators and comprising water containing a very small amount of complex condensation products derived by the reaction between certain acylated polyamines, acylated hydrazines, etc. with coupling agents productive of polyacylated products as more fully described hereinbelow. When water containing small amounts of these substances is heated to the boiling point in a steam boiler or other generator, being thereby evaporated, the concentration of solids therein will not bring about excessive foaming and the resulting priming, these compounds being substantially nonvolatile with the steam and stable, so that they will be retained by the water and neither they nor their decomposition products will appear in the steam and the resulting condensation thereof.

It is well known in the operation of steam boilers, such as in electric power plants, railroad locomotives and the like, or in evaporators, that the water therein, even though initially it shows very little tendency to foam, will, when the amount of total solids therein approaches a relatively high concentration, develop a very decided tendency to foam. When this occurs, considerable quantities of water are physically carried out of the boilers or evaporators with the steam, thus appearing in the steam lines and in the eventual condensate. Such priming has many disadvantages because it tends to contaminate the steam lines, to plug or corrode the valves, and under serious conditions may even impair the cylinders and piston rods of the steam engines, or the impeller blades of turbines in which the steam is used for the generation of power. Attempts have been made in the past to control this foaming, either by excessive blowdown of the boilers or by the injection thereto of such materials as castor oil, tallow, and the like. While these fatty materials have some small degree of efficiency, they are, on the other hand, quite deficient in that they introduce new difficulties which, in some instances, are worse than the conditions they are intended to cure. In the first place, these fatty

2

acids or glycerides are unstable under the conditions existing in the boilers, particularly as the pressure and temperature increases, the high temperatures leading to rapid decomposition of the glycerides, which, if anything, will tend to increase the foaming and priming difficulties. Furthermore, in many instances certain of the decomposition products thus produced, or sometimes even the materials themselves, have a definite volatility with steam and will, therefore, steam-distil out of the boilers, thus appearing in the steam and in the condensate. This, of course, is also very undesirable. Furthermore, such types of antifoaming agents usually have to be employed in relatively large quantities, adding not only to the expense but also to the inconvenience of operating the steam generators; and those which have a tendency to decompose do so quite rapidly, and hence their effectiveness is of short duration, which therefore necessitates the continual charging into the boilers or other steam generators of considerable amounts of these older antifoaming agents. Moreover, such antifoaming agents are difficult to use because the amounts in which they are efficacious are very critical, and any over-dosage usually aggravates the difficulty instead of curing it.

It has now been found that compounds of the nature already hereinabove indicated are highly efficient antifoaming and antipriming agents for use in steam generators. These compounds can be considered as being polyacylated polyamines, which can be obtained by a number of different methods. Thus it is possible to couple monoacylalkylenediamines, monoacylhydrazines, monoacylarylenediamines, acylated polyalkylenepolyamines, monoacylpiperazines and the like by means of, for example, dichloroacetone, formaldehyde and its polymers, dichloroethylene (1,2-dichloroethane) or combinations of a dihalide plus a polyamine concurrently.

Particularly useful products may be obtained by coupling two or more already acylated polyamines with (a) certain organic dihalides, (b) formaldehyde or its polymers, (c) an alkylene dihalide and an alkylenepolyamine concurrently, or (d) an acylated hydrazine with *s*-dichloroacetone, formaldehyde, etc.

Materials coming within the scope of the present invention produced by the coupling of diacyl polyalkylenepolyamines, may be represented by the following probable general formula:

wherein X and Y are aliphatic hydrocarbon radicals which may contain one or more double bonds and may contain hydroxyl groups, that is, X—CO— and —OC—Y are acyl radicals derived from aliphatic and hydroxyaliphatic acids; R and R' represent hydrogen or methyl; x is zero or a small whole number; and Z is an alkylene group which may contain a carbonyl group, one or more amino nitrogens, or an ether linkage.

Examples of this type of material which are prepared from monoacylated polyamines may be represented by the probable general formula:

wherein X is an aliphatic hydrocarbon radical which may contain one or more double bonds and may contain hydroxyl groups, that is, X—CO— and —OC—X are the acyl radicals of aliphatic or hydroxyaliphatic acids; Y may be the alkylene or arylene residue of a polyamine; and Z is an alkylene group which may contain a carbonyl group, one or more amino nitrogens or an ether linkage. In case of hydrazine derivatives the constituent Y will obviously be absent. Hydrazine is to be considered as a type of polyamine for the present purpose.

It is to be understood that the formulas recited in the claims are "probable" in that the formulas given are believed to be possessed by the compounds disclosed, or whose method of preparation is disclosed in this specification.

Some specific examples of the above products are those resulting from the condensation of about two mols of dioleyldiethylenetriamine and one mol of ethylene dichloride; (2) the product resulting from the condensation of about 2 mols of dilauryldiethylenetriamine with one mol of ethylene dichloride; (3) the product resulting from the reaction of about one mol of dilauryldiethylenetriamine and one mol (100% excess) of formaldehyde in the presence of hydrogen chloride; (4) the product resulting from the reaction of dioleyldiethylenetriamine and an excess of formaldehyde, in the presence of sulfuric acid; (5) the product resulting from the condensation of about 3 parts of dioleyldiethylenetriamine and 2 parts of a complex amine-containing dihalide formed by the preliminary condensation of equal parts of triethylenetetramine and ethylene dichloride; and (6) the product resulting from the concurrent reaction of about one mol of ethylene dichloride and about one mol of diethylenetriamine with one mol of dioleyldiethylenetriamine.

It has been found that an important factor in determining the efficiency of these materials as antifoam agents is their total molecular weight. Thus, where it is necessary to use relatively long acyl radicals in a derivative carrying only a few such groups, it is sufficient to use only one or two heavy acyl groups in a derivative that also bears several shorter acyl radicals, e. g., acetyl. In general it can be said that if the derivative contains at least about 30 carbon atoms, it will be of value. An increase in the number of carbon atoms over this figure generally results in an increased efficiency, although the two variables are not directly related. A further advantage to be gained by operating under several of the methods of the present invention, wherein the alkyleneamine groups of the product are multiplied, is that this type of condensation products usually is readily dispersible in water, and thus may be simply employed, or may require very little of an auxiliary dispersing agent.

The following examples are intended to illustrate typical preparations within the scope of the present invention, but are not to be construed as limiting the invention beyond the appended claims.

Example 1.—15.7 grams (0.05 mol) of mono-stearylhydrazine is condensed with 3.2 grams (0.025 mol) of s-dichloroacetone at 150–160° C. for one hour with stirring.

Example 2.—15.7 grams (0.05 mol) of mono-stearylhydrazine is condensed with 3.2 grams (0.025 mol) of 1,3-dichloro-2-propanol at 150–160° C. for one hour with stirring.

Example 3.—15.7 grams (0.05 mol) of mono-stearylhydrazine is condensed with 1.501 grams (0.05 mol, 100% excess) trioxymethylene at 150–160° C. for one hour with stirring.

Example 4.—1.6333 grams (0.01666 mol) of ethylene dichloride is carefully weighed out into a small flask. 21 grams (0.0333 mol) of dioleyldiethylenetriamine is added and the flask is fitted with a Hopkins reflux condenser. The mixture is warmed on the steam cone for 24 hours, and the reaction is completed by heating at 150–160° C. for one hour with stirring. The resulting compound possesses antifoam properties.

Example 5.—11.6 grams (0.025 mol) of dilauryldiethylenetriamine is treated with 1.25 grams (0.013 mol) of ethylene dichloride at 150–160° C. for 3 hours with stirring. The product is a hard, brown wax.

Example 6.—11.6 grams (0.025 mol) of dilauryldiethylenetriamine is condensed with 2 grams (0.0266 mol) of 40 percent formaldehyde and 0.5 cc. concentrated hydrochloric acid. The reaction mixture is heated at 150–160° C. for 3 hours with stirring. The product is a soft, brown wax.

Example 7.—Dioleyldiethylenetriamine is heated at 150–160° C. with an excess of 40 percent formaldehyde and stirred for 3 hours. The product is a soft paste-like wax. This wax is treated with $\frac{1}{3}$ its weight of concentrated sulfuric acid sp. gr. 1.84) at 100° C. The material immediately condenses to form a black, lumpy product.

Example 8.—17 grams of triethylenetetramine is mixed with 17 grams of ethylene dichloride and the flask is fitted with a reflux condenser. The mixture is warmed until the reaction is initiated and then cooled externally to moderate the violence of the reaction. After the preliminary reaction has subsided, the compound is stirred at 170–175° C. for 4 hours. Eight grams of the polymer thus obtained above and 0.1 gram of potassium hydroxide are added to 12 grams of dioleyldiethylenetriamine and stirred at 150–160° C. for 4 hours. The resulting product is completely dispersible in water and has excellent antifoam characteristics.

Example 9.—63.1 grams (0.1 mol) of dioleyldiethylenetriamine is placed in a 200 cc. 3-necked round-bottomed flask fitted with a mechanical stirrer and two dropping funnels. One dropping funnel is charged with 10.5 grams (0.102 mol) of diethylenetriamine, and the other with 11.9 grams (0.12 mol) of ethylene dichloride. The flask is heated by an oil bath at a temperature of 150–160° C. The stirrer is then started and the dropping funnels so adjusted that the addition of both liquids is completed during 15 minutes. The reaction mixture is stirred at 150° C. for 5 minutes longer to complete the reaction.

Example 10.—132 grams (0.282 mol) of dilauryldiethylenetriamine is condensed at 150–160° C. with 29 grams (0.282 mol) of diethylenetri-

triamine and 28 grams (0.282 mol) of ethylene dichloride for one hour with stirring. The light brown wax obtained by this method is a very good antifoam material.

Example 11.—4.95 grams of ethylenedichloride is added dropwise during twenty minutes to 15.7 grams of monostearylhydrazine at 150–160° C. The resulting mixture was then stirred at this temperature for one hour to complete the reaction.

Example 12.—9.0 grams of monostearylhydrazine is condensed with 0.75 grams of trioxymethylene at 150–160° C., while stirring for one hour. The product is a brown wax.

Example 13.—9.0 grams of monostearylhydrazine is condensed with 1.6 grams of s-dichloroacetone at 150–160° C. for one hour. The product is a brown wax.

The compounds described in the above examples, while they differ somewhat from each other in their relative efficiency as antifoaming material, are all serviceable as such. Many of them are readily dispersible in water, so that they need merely be dispersed in the water which is to be rendered nonfoaming under boiler service conditions. In the case of some of the compounds, these may be dispersed by emulsification, and the emulsions thus obtained may then be introduced by suitable feeding means into the boiler or into the feed water entering the same.

The amounts of the above-mentioned compounds which are required are extremely small, and in general one grain per gallon is ample. For many purposes, however, amounts as little as $\frac{1}{100}$ grain per gallon in the feed water will still give valuable results, and the amounts may be even further reduced. Depending of course upon the degree of concentration of solids, the dosage may be varied, but one grain per gallon is about as much as would ever have to be used even under serious conditions, and for many purposes $\frac{1}{100}$ grain per gallon and even less can be used. The process is particularly effective at pressures of about 250 pounds per square inch.

The introduction of the antifoaming compounds of the present invention into the boiler may be accomplished in a number of ways. Thus, the antifoaming compositions may be dispersed or physically mixed with, say, sodium carbonate or some other material used for treating the boiler water and pumped with the feed water into the boiler by means of either an injector or a feed water pump. The compounds may also be dissolved in suitable organic water-miscible solvents such as alcohols, ethers, ketones, etc. and introduced in small measured amounts into the feed water entering the boiler. Suitable mechanical measuring devices which will periodically or continuously inject the required dosage of the antifoaming compounds into the feed water may be used, so that the introduction will be more or less in proportion to the steam consumption to which the steam generator is subjected. The invention therefore is not to be limited by the manner of introduction of the antifoaming composition but rather is to be construed in the terms of the hereunto appended claims.

We claim:

1. A method of generating steam which comprises boiling, under superatmospheric pressure conditions, water containing an amount of total dissolved solids tending to produce foaming and priming and a quantity of the product of condensation of about 2 mols of monostearyl hydrazine with about 1 mol of s-dichloroacetone, said

quantity being sufficient to substantially inhibit said foaming and priming.

2. A liquid for the generation of steam, substantially devoid of foaming and priming tendencies when heated to the boiling point, comprising water containing an amount of total dissolved solids tending to produce foaming and priming and a quantity of a condensation product of about 2 mols of monostearyl hydrazine 10 and 1 mol of s-dichloroacetone, said quantity being sufficient to substantially inhibit said foaming and priming.

3. A method of generating steam which comprises boiling, under superatmospheric pressure 15 conditions, water containing an amount of total dissolved solids tending to produce foaming and priming and a quantity of a wax-like coupled partially acylated polyamine in which one mol of a partially acylated polyamine is coupled to another mol of a similar partially acylated polyamine through a group from the class consisting of simple alkylene radicals, alkylene radicals containing a carbonyl group and alkylene radicals containing at least one amino nitrogen, no alkylene radical in said group containing more than 3 carbon atoms, said coupled partially acylated polyamine containing at least 30 carbon atoms, and said quantity being sufficient to substantially inhibit said foaming and priming.

4. A liquid for the generation of steam, substantially devoid of foaming and priming tendencies when heated to the boiling point, comprising water containing an amount of total dissolved solids tending to produce foaming and priming and a quantity of a wax-like coupled partially acylated polyamine in which one mol of a partially acylated polyamine is coupled to another mol of a similar partially acylated polyamine through a group from the class consisting of simple alkylene radicals, alkylene radicals containing a carbonyl group and alkylene radicals containing at least one amino nitrogen, no alkylene radical in said group containing more than 3 carbon atoms, said coupled partially acylated polyamine containing at least 30 carbon atoms, and said quantity being sufficient to substantially inhibit said foaming and priming.

5. A method of generating steam which comprises boiling, under superatmospheric pressure conditions, water containing an amount of total dissolved solids tending to produce foaming and priming and a quantity of a condensation product as claimed in claim 3 wherein the partially acylated polyamine is monostearylhydrazine, said quantity being sufficient to substantially inhibit said foaming and priming.

6. A liquid for the generation of steam substantially devoid of foaming and priming tendencies when heated to the boiling point comprising water containing an amount of total dissolved solids tending to produce foaming and priming and a quantity of a condensation product as claimed in claim 4 in which the partially acylated polyamine is monostearylhydrazine, and said quantity being sufficient to substantially inhibit said foaming and priming.

7. A method of generating steam which comprises boiling, under superatmospheric pressure conditions, water containing an amount of total dissolved solids tending to produce foaming and priming and a quantity of the product of condensation of about 2 mols of dioleyldiethylenetriamine and 1 mol of ethylene dichloride, said quantity being sufficient to substantially inhibit 75 said foaming and priming.

8. A liquid for the generation of steam substantially devoid of foaming and priming tendencies when heated to the boiling point comprising water containing an amount of total dissolved solids tending to produce foaming and priming and a quantity of the product of condensation of about 2 mols of dioleyldiethylenetriamine and 1 mol of ethylene dichloride and said quantity being sufficient to substantially inhibit said foaming and priming.

9. A method of generating steam which comprises boiling, under superatmospheric pressure conditions, water containing an amount of total dissolved solids tending to produce foaming and priming and a quantity of the product of condensation of about 2 mols of dilauryldiethylenetriamine with about 1 mol of ethylene dichloride, said quantity being sufficient to substantially inhibit said foaming and priming.

10. A liquid for the generation of steam substantially devoid of foaming and priming tendencies when heated to the boiling point comprising water containing an amount of total dissolved solids tending to produce foaming and priming and a quantity of the product of condensation of about 2 mols of dilauryldiethylenetriamine with about 1 mol of ethylene dichloride, and said quantity being sufficient to substantially inhibit said foaming and priming.

11. A method of generating steam which comprises boiling, under superatmospheric pressure conditions, water containing an amount of total dissolved solids tending to produce foaming and priming and a quantity of the product resulting from condensation of about 3 parts of dioleyl-

5 diethylenetriamine and 2 parts of a complex amine-containing dihalide formed by the preliminary condensation of equal parts of triethylene tetramine and ethylene dichloride, said quantity being sufficient to substantially inhibit said foaming and priming.

10 12. A liquid for the generation of steam substantially devoid of foaming and priming tendencies when heated to the boiling point comprising water containing an amount of total dissolved solids tending to produce foaming and priming and a quantity of the product resulting from the condensation of about 3 parts of dioleyldiethylenetriamine and 2 parts of a complex amine-containing dihalide formed by the preliminary condensation of equal parts of triethylene tetramine and ethylene dichloride, and said quantity being sufficient to substantially inhibit said foaming and priming.
